UNITED STATES PATENT OFFICE.

IZIDOR BUCHLER, OF NEW YORK, N. Y., ASSIGNOR TO LOUIS B. WASSERSTROM, OF NEW YORK, N. Y.

STROPPING-MACHINE.

1,011,571.

Specification of Letters Patent.

Patented Dec. 12, 1911.

Application filed May 3, 1909. Serial No. 493,467.

To all whom it may concern:

Be it known that I, IZIDOR BUCHLER, a subject of the Emperor of Austria-Hungary, residing at the city of New York, in the county of New York and State of New York, have invented certain new and useful Improvements in Stropping-Machines, of which the following is a specification.

My invention relates to that class of razor-stropping machines in which a looped strop bears against a shaft, which is oscillated as the two ends of the strop are pulled back and forth and causes a razor holder to move from side to side.

The object of the invention is to simplify the construction of such stropping machines and at the same time to attain a high degree of durability and efficiency.

To this end the invention may be said to consist in the various novel features and arrangements of parts set forth in the appended claims and fully described in the following specification.

In the accompanying drawings, Figure 1 is a side view of the improved stropping machine; Fig. 2 is an end view; Fig. 3 is a view of the other end of the device; Fig. 4 is a section corresponding to Fig. 1, being on an enlarged scale; and Fig. 5 is an enlarged end view.

Referring now to these views, the numeral 1 designates the framework of the device as a whole. One of the features of the invention resides in the simple, yet strong and effective construction of this framework. It comprises primarily a top frame 2 and two side frames 3. The top frame 2 consists simply of a metal plate, having its end portions 4 bent downward at substantially right angles. The side frames 3 are pivotally or hingedly connected, in spaced relation, near their upper ends, to the lower portions of these end portions 4. Each side frame 3 consists preferably of two substantially L-shaped plates 5, the upper ends of which are pivoted as described, at 6, to the end portions 4 of the top frame 2, and which are united by two rods 7 and 8, connecting, respectively, the side and bottom bars of the L-shaped plates 5. These rods 7 and 8 serve also as guides for the strop 9, the two portions of which are threaded between the

members of the two pairs of rods. In operation, the strop 9 bears against the outer sides of the rods 8, which, obviously, might be in the form of rollers; and the rods 7 might, if desired, be omitted. The inner ends of the bottom bars of the L-shaped plates 5 abut against each other, when the framework is closed, whereby there is afforded a sufficient opening through from end to end of the framework for the accommodation of the razor. To insure that the framework will not open at an inconvenient moment, a yielding catch may be employed to connect said side frames 3. A simple form of such catch is illustrated in the form of a resilient plate 10, secured to the inner face of the bottom bar of one of the L-shaped plates 5 and provided with a boss 11 that co-operates with a socket 12 on the inner face of the opposed L-shaped plate 5 of the other side frame. Thus, the side frames 3 may be snapped shut and open, without the necessity of handling the catch itself. In order to lend further rigidity to the framework when closed than is afforded by the abutting of the inner ends of the bottom bars of the L-shaped plates 5, one or both of the said L-shaped plates may be provided above the pivots 6 with hooks or extensions 13 that bear against studs or projections 14 on the inner surfaces of the plates 5. These extensions 13 may serve, on the other hand, to limit the degree of opening of the side frames 3, by contacting with any suitable stop, as the enlarged end 15 of the shaft 16 of the razor-holder 17. The strop 9 is looped about an actuating shaft 18 journaled in the end portions 4 of the top frame 2. This shaft is geared to the shaft 16 below, as by mutilated spur gears 32. The razor-holder 17 is carried by the shaft 16, and has converging side walls 19, spaced apart slightly at the bottom. Between these walls the razor blade is slipped endwise, and is held in position by a bowed spring 20 secured to the inside of the top of the holder. One end of the spring 20 is preferably bent downward, as at 21, to constitute a stop against which the end of the razor blade abuts. It will be obvious that the razor-holder might be constructed to hold the blades of safety razors.

An important feature of the invention resides in the provision of a detent carried or otherwise actuated by yielding supporting means for the framework 1, whereby the detent is normally in locking relation with respect to the razor-holder but is moved to release the razor-holder when pull is exerted on the ends of the strop. Naturally there may be numerous embodiments of this detent. A desirable form is illustrated, in which a sliding bar or plate 22 extends between the portions 4 of the top plate 2, the ends 23, 24 of this bar being reduced and moving in vertical slots 25 in the portions 15 4 of the plate 2. The end part 23 of the bar 22 constitutes the detent proper, being designed to engage with a suitable socket 26 formed in an enlargement or plate on one end of the actuating shaft 18. However, the 20 detent might well engage with another part, if desired. The detent is held normally in engagement with the socket by means of a spring or springs 27, interposed between the plate 2 and the bar 22. These springs are 25 desirably coiled about guiding posts 28 secured to the plate 2 and passing through openings 29 in the bar 22. A hanging hook or eye 30 is secured to the bar 22 and projects upward through an opening 31 in the 30 top plate 2. The bar 22 also serves to brace the top frame 2. Thus, the razor-holder is normally held stationary, so that danger of cutting, through wobbling of the holder, when the razor is being inserted or removed, 35 is eliminated. When the device 30 is secured to any suitable anchorage and pull is exerted upon the ends of the strop, the whole framework 1 is drawn downward or outward with respect to the bar 22, so that the 40 detent is released, and reciprocation of the strop results in the razor-holder being swung from side to side in co-operative relation with the successive out-going portions of the strop. The resilient support of the 45 framework of the machine is of advantage in affording an easier stropping action.

While the preferred embodiment of the invention has, for sake of clearness, been described in considerable detail, it will be 50 obvious that numerous changes may be made without departing from the scope of the invention.

What I claim as new is:—

1. A stropping machine comprising a 55 framework, a strop looped therein, a razor-holder adapted to be moved from side to side by reciprocation of said strop, a movable detent adapted to be shifted out of engagement with said razor-holder by the pull 60 on the strop during the stropping operation, and a spring for automatically returning said detent into engagement with said razor-holder when the stropping operation ceases.

2. A stropping machine comprising a 65 framework, a strop looped therein, a razor-holder adapted to be moved from side to side by reciprocation of said strop, and a detent adapted to be shifted automatically into and out of engagement with said razor- 70 holder when the stropping operation ceases and commences, respectively.

3. A stropping machine comprising a framework, a strop looped therein, a razor-holder adapted to be moved from side to 75 side by reciprocation of the strop, supporting means yieldingly and resiliently connected to said framework, and a detent normally held by said yielding supporting means in locking relation to said razor-holder.

4. A stropping machine comprising a framework including a top plate, a movable razor-holder, a looped strop adapted by its reciprocation to move said razor-holder from 85 side to side, a movable bar parallel to said top plate, a detent adapted to be actuated by said bar, resilient connection between said plate and bar tending to cause said detent to engage with said razor-holder, and supporting means connected with said bar.

5. A stropping machine comprising a framework including a top plate, a movable razor-holder, a looped strop adapted by its reciprocation to move said razor-holder from 95 side to side, a movable bar parallel to said top plate, a detent adapted to be actuated by said bar, guiding posts and surrounding coil springs between and connecting said plate and bar, said springs tending to cause 100 said detent to engage with said razor-holder, and supporting means connected with said bar.

6. A stropping machine comprising a framework including a top plate provided 105 with an aperture, a movable razor-holder, a looped strop adapted by its reciprocation to move said razor-holder from side to side, a movable bar beneath said top plate, a detent adapted to be actuated by said bar, resilient connection between said plate and bar tending to cause said detent to engage 110 with said razor-holder, and a supporting device carried by said bar and projecting through said aperture in the top plate.

7. A stropping machine comprising a framework including a top plate, a movable razor-holder, a looped strop adapted by its reciprocation to move said razor-holder from side to side, a movable bar parallel to 120 said top plate, a detent carried thereby, resilient connection between said plate and bar tending to cause said detent to engage with said razor-holder, and supporting means connected with said bar.

8. In a stropping machine, a blade holder, a strop, and locking means movable into and out of interlocking engagement with said

blade holder, said locking mechanism being releasable by producing tension on the strop.

9. In a stropping machine, a blade holder, a strop, and spring actuated means for automatically locking said blade holder in an inoperative position, said locking mechanism being movable to a position substantially free from the blade holder by producing tension on the strop.

10. In a stropping machine, a supporting member, a frame having reciprocating movement with reference thereto, a blade holder, means for automatically locking said blade holder in its inoperative position, and means operated by a forward movement of said frame for releasing said locking means.

11. In a stropping machine, a reciprocating frame, a blade holder, a strop, means cooperating with the strop whereby a to and fro motion is imparted to said blade holder, means rearwardly of a looped portion of the strop for locking said blade holder in its inoperative position, and means actuated by producing tension on the strop for releasing the blade holder from its locked position.

12. In a stropping machine, a blade holder, a roller coöperating therewith, and locking mechanism rearwardly of the roller for securing said blade holder in its inoperative position.

13. In a stropping machine, a hanger, a frame slidable with respect thereto, tension means for imparting movement in one direction thereto, a blade holder, and locking means controllable by the slidable movement of the frame for locking said blade holder in its inoperative position.

14. In a stropping machine, a blade holder, a roller coöperating therewith, a hanger, and a tongue and groove on the hanger and the roller whereby the blade holder may be locked in position.

15. In a stropping machine, a frame, a blade-holder, said frame and blade-holder being movable relatively one to the other, a strop, and locking means acting normally to retain the blade holder substantially free from engagement with the strop, said locking means being releasable by the action of the strop.

16. In a stropping machine, a frame, a blade-holder, said frame being shiftable relatively to the blade-holder, a strop, and locking means operated by the movement of the strop.

17. In a stropping machine, a movable frame, a blade holder, a strop, and locking means for said blade holder and movable relative to the blade holder, said locking means and the movement of the frame being controlled by the action of the strop.

18. In a stropping machine, a frame, a

strop mounted therein, a blade holder movable relative to the strop, and locking mechanism for said blade holder, said locking mechanism and the blade holder being movable relative to each other by producing tension on the strop.

19. In a razor sharpener, in combination with a blade holder adapted to oscillate, a spring arranged to maintain said holder in the middle of its oscillatory range and means for disengaging the spring from the holder actuated by drawing on the polishing strop, substantially as described.

20. In a stropping machine a framework consisting of a top frame and two side frames pivoted thereto, a catch for holding said side frames together, said catch being yieldable in both directions, whereby said side frames may be sprung shut and open without handling the catch.

21. A stropping machine comprising a framework consisting of a top frame and two side frames hinged to said top frame, a razor-holder, and a looped strop adapted to move said razor-holder from side to side, said side frames having stop portions, and stops carried by said top frame against which said strop portions are adapted to abut when said side frames are closed.

22. A stropping machine comprising a framework consisting of a top frame and two side frames hinged to said top frame, a razor-holder, and a looped strop adapted to move said razor-holder from side to side, said side frames having upper hook-extensions, and projections on said top frame with which said hook-extensions are adapted to engage when said side frames are closed.

23. In a stropping machine, a razor-holder having downward converging walls, and a bowed spring therein having an end portion turned down to constitute an end stop for the razor.

24. A stropping machine comprising a framework consisting of a top frame formed of a plate having downturned ends, side frames pivoted to said downturned ends, a razor holder mounted in said top frame, a vertically slidable bar mounted at its ends in said downturned ends of the top frame and constituting a brace for the same, a detent carried by said bar adapted to lock said razor holder, resilient connection between said bar and said top frame, and supporting means carried by said bar.

25. A stropping machine comprising a framework including a top plate, a movable bar, supporting means connected to said bar, resilient connection between said plate and bar, a razor-holder, and a looped strop adapted to move said razor-holder from side to side.

26. A stropping machine comprising a

framework consisting of a top frame formed of a plate having downturned ends, side frames pivoted to said downturned ends, a razor-holder mounted in said top frame, an actuating shaft also mounted in said top frame, gears mounted on and operatively connecting said operating shaft and razor holder, a vertically slideable bar mounted at its ends in said downturned ends of the

top frame, a detent carried by said bar 10 adapted to lock said razor holder, resilient connection between said bar and said top frame, and supporting means carried by said bar.

IZIDOR BUCHLER.
